UNITED STATES PATENT OFFICE.

COMMODORE PERRY SNELL, OF ST. PETERSBURG, FLORIDA.

DESIGN FOR A CURBING SECTION.

Application filed October 19, 1925. Serial No. 15,169. Term of patent 3½ years.

To all whom it may concern:

Be it known that I, COMMODORE PERRY SNELL, a citizen of the United States, residing at St. Petersburg, in the county of Pinellas and State of Florida, have invented a new, original, and ornamental Design for Curbing Section, of which the following is a specification, reference being had to the ac-

companying drawing, forming a part thereof.

The figure is a perspective view of the curbing section.

I claim:

The ornamental design for a curbing section, as shown.

C. PERRY SNELL.
